UNITED STATES PATENT OFFICE.

DAVID S. WATSON, OF CANASTOTA, NEW YORK.

FIRE-PROTECTIVE SHIELD.

1,181,188.

Specification of Letters Patent.

Patented May 2, 1916.

Application filed May 31, 1911. Serial No. 830,284.

To all whom it may concern:

Be it known that I, DAVID S. WATSON, of Canastota, in the county of Madison, in the State of New York, have invented new and useful Improvements in Fire-Protective Shields, of which the following, taken in connection with the accompanying drawings, is a full, clear, and exact description.

This invention relates to certain improvements in fire protective shields for floor openings of the class set forth in my Patents Nos. 848,583, March 26, 1907; 889,737, June 2, 1908; 900,248, October 6, 1908; 1,038,283, April 8, 1918, and 1,100,003, June 15, 1914, and the patent to R. J. Kittredge 10, 1,021,585, March 26, 1912, of which I am now the sole owner, and also to my pending application No. 716,560, which is a reissue of my Patent No. 1,032,717, except that the 15 tilting shield is provided with self-closing sliding gates normally held open by separate heat controlled devices, and is also provided with means for closing the portions of the floor opening which may be left open by the 20 tilting of the shield, all of these parts being carried by the tubular shell to form a unitary structure.

The primary object, therefore, of my present invention is to provide a combined 30 guide chute and fire protective shield which may be held in a vertical position or at different angles thereto according to the direction in which it may be desired to pass the articles through such opening.

Another object is to provide heat controlled means for closing the opening through the chute when the heat surrounding the chute reaches a predetermined degree and to render the same closure operative in any position of the chute.

A further object is to provide one or more guard plates or covering pieces which are adjustable relatively to the chute to cover any intervening gap between the sides of 45 the floor opening and adjacent portion of the chute.

Other objects and uses will be brought out in the following description.

In the drawings, Figures 1 and 2 are respectively side and front elevations of a

combined guide chute and fire shield in operative position in a floor opening. Fig. 3 is a longitudinal vertical sectional view through the same chute or shield taken on line 3—3, Fig. 2. Figs. 4 and 5 are respectively a transverse sectional view and a lengthwise sectional view of said chute taken respectively on lines 4—4 and 5—5 Fig. 1.

This device is adapted to be used in connection with any wall, floor or partition opening but is more particularly useful in connection with an opening as —a— in a floor —A— through which lumber and other articles of merchandise are adapted to be passed from floor to floor and comprises in its organization a tubular chute —1— and separate supporting members —2— together with heat controlled means hereinafter described for closing the opening through the chute when the local heat reaches or exceeds a predetermined degree of temperature, all parts of the device except the heat destructible detents for the closures being made of heat resisting material such as sheet or cast metal.

The chute —1— preferably consists of an elongated metal tube of substantially rectangular cross section open at both ends to allow the passage of articles therethrough, the cross sectional area being somewhat less than that of the opening —a— through which it projects to allow the chute to be adjusted to the desired angle.

The supporting members —2— preferably consist of cast metal brackets separately connected to the chute —1— by pivotal bolts —3— to permit the chute and brackets to be adjusted relatively to each other and are provided along their upper edges with out-turned flanges —4— of greater length than the width of the opening —a— for securing to the underside of the floor by suitable fastening means as bolts or screws —5—.

The pendant main bodies of the brackets —2— are substantially flat and are disposed in close proximity to opposite sides of the chute with just sufficient clearance to allow the chute to be tilted relatively thereto and are provided with slots —6— below and concentric with their respective pivotal bolts —

—3— for receiving clamping bolts —7— and permitting relative tilting adjustment of the chute and brackets one upon the other, the clamping bolts —7— serving to hold 5 such parts in their relatively adjustable positions. The upper sides of the brackets are recessed for receiving the ends of separate guard plates or filling pieces —8— which are located at the front and rear of 10 the chute and are adjustable relatively there-to so as to bring their inner edges into more or less proximity to the adjacent faces of said chute. The inner edges of these plates are provided with downwardly deflected 15 flanges —9— of substantially the same width as the chute for the purpose of deflecting any local flame or fire downwardly away from the opening. The portions of 20 these guard plates adjacent the floor —A— may be covered with a layer of asbestos or similar non-conductor of heat to prevent the transmission of heat from the metal to the wood, said plates being clamped between the upper faces of the brackets —2— and under 25 side of the floor as best seen in Figs. 2 and 3. The downwardly deflected flanges —9— on the inner edges of the plates —8— also serve the purpose of deflecting the heat away from the adjacent portion of the wood floor 30 around the opening —a— leaving the intervening air space to further protect the floor from burning or charring in case the metal should become excessively heated. The main function, however, of these plates is to cover 35 the intervening space between the sides of the opening and adjacent portions of the chute and for this purpose they may be adjusted upon the brackets relatively to the chute so as to effectively cover the opening 40 —a— in the floor when the chute is tilted to different angles. This chute extends through the opening —a— and above the upper surface of the floor to prevent accidental dis- 45 placement of articles upon the floor into the chute, said chute also extending a considerable distance below the floor into the under-lying room or apartment so as to prevent any fire or smoke which may rise to the ceiling from passing out through the floor open- 50 ing or through the chute.

The heat controlled means for closing the opening through the chute preferably consists of one or more, in this instance, two, sliding gates or closures —10— and —11— 55 which are normally held in their open positions by fusible detents —12— and —13— and are adapted to be automatically closed when the detents are disintegrated by heat by weighted members —14— and —15—. 60 These gates —10— and —11— are preferably located in or upon the lower portion of the chute one above the other, the gate —10— being disposed in an inclined position or at an acute angle with the upper por-

tion of the chute and is guided in corre- 65 spondingly inclined ways or grooves —16— in the sides of the chute and extensions —17—. The lower gate —11— is disposed at substantially right angles to said chute and is guided in grooves —18— in opposite sides 70 of the chute and suitable extensions —19— as best seen in Figs. 3 and 5. I have shown the chute as provided with a plurality of gates or closures arranged at different angles so as to permit a wider range of adjust- 75 ment of said chute with the assurance that at least one or both of the gates will be automatically closed in case of fire. I have shown the gates as held in their open positions by fusible detents adapted to be dis- 80 integrated by a predetermined degree of heat localized around the chute but it is evi- 85 dent that the gates may be held open by their heat controlled means. These fusible detents —12— and —13— are of well known link construction not necessary to herein illustrate or describe, the fusible link —12— being connected at one end to a hook —21— on the outer end of the gate —17— while its other end is connected to a hook —22— 90 projecting from the adjacent side of the chute. In like manner the fusible link —13— is connected at one end to a lever or weighted arm —23— and its other end is connected to a hook-shaped member —24— 95 on the adjacent side of the chute, said arm —23— being V-shape and having one end pivoted at —25— to the adjacent side of the chute —1— and its other end provided with the weight —15—, said arm having its 10 intermediate portion or apex loosely connected to the outer end of the gate —11—.

It is now clear that in case of fire in the room or apartment below the floor —A— any flame or heat which may rise to the ceiling around the opening —a— will destroy the detents —12— and —13— and allow the gates —10— and —11— to be automatically closed by their weights —14— and —15— respectively, thus preventing any 1 possibility of fire and smoke passing through the chute, and together with the bracket —2— and guard plates —8— effectively prevent the passage of fire and smoke through the floor opening.

Additional shield plates —30— may be secured to the floor around the upwardly protruding end of the chute to positively close the upper end of the floor opening and thereby prevent accumulations of dust and other foreign matter therein.

The asbestos filling between the plates —8— and underside of the floor may be extended to the space between the brackets —2— and underside of the floor so as to guard against transmission of heat from the brackets or plates to the wood.

In order to prevent interference with the

free operation of the gates by corrosion, said gates or their guides may be made of brass or copper.

What I claim is:

5 A fire protective shield for floor openings comprising a tubular shell having an opening therethrough from end to end, self-closing gates movable across the opening and spaced some distance apart to form an in-

tervening dead-air chamber when closed, 10 and thermally released detents for the gates.

In witness whereof I have hereunto set my hand on this 17th day of May, 1911.

DAVID S. WATSON.
